YIELDABLE SUPPORT FOR VIBRATORY MECHANISMS

Albert R. Miller, Hialeah, Fla.

Original application April 8, 1943, Serial No. 482,292. Divided and this application May 9, 1945, Serial No. 592,894

1 Claim. (Cl. 248—20)

1

This invention relates to washing machines used for laundering clothes, and more particularly to machines of this class which are automatic in their operation, having for its object to provide a construction which is sturdy and well adapted to withstand and/or absorb the considerable amount of vibration and strains which are inherent in such machines during their operation.

With these and other objects in view, the invention resides in the novel details of construction and combinations of parts as will be disclosed more fully hereinafter and particularly covered by the claim.

This application constitutes a division of my application for patent filed April 8, 1943, under the Serial No. 482,292 and entitled Washing machine and method of washing.

Referring to the accompanying drawings forming a part of this specification and in which like numerals designate like parts in all the views—

Fig. 1 is a view, partly in section and partly in elevation, of the parts illustrated in Fig. 4 as seen substantially on the line 1—1 of that figure and looking in the direction of the arrows;

Fig. 2 is a detail view in elevation of one of the yieldable connections between the cylinder support and the tub support of the machine;

Fig. 3 is a vertical sectional view taken as on the line 3—3 of Fig. 2 and looking in the direction of the arrows; and

Fig. 4 is a front elevational view, partly in section, of the parts shown in Fig. 1.

While it is obviously conceivable that this invention is applicable to any apparatus comprising a relatively static portion which supports another portion involving moving parts and/or vibratory elements yet, for the purpose of exemplification only, the invention is herein illustrated as applied to the automatic washing machine forming the subject matter of the application for patent of which this instant application is a division. Consequently the drawings and reference numerals used herein have been copied from the parent application, wherefore all that was heretofore disclosed and described therein is equally applicable to, and true with respect of, the corresponding constructions illustrated herein.

That is to say, the numeral 2 designates a receptacle which is divided transversely by a substantially vertical partition to form two open top tanks or tubs of equal or different capacities as desired, one tub serving as the soak and rinse tub, and the other serving as the wash tub, the tub 5 being particularly illustrated. The bottoms of these two tubs preferably are of circular formation as shown in Fig. 1 to facilitate drawing of the water therefrom as through the respective drain pipes 6 and 7 into a funnel-like collector 8 adapted to communicate with any suitable

medium by which the drained water may be removed from the machine.

The receptacle 2 is supported in any convenient manner upon a suitable rigid framework including legs such as 9 contacting the floor. Horizontally disposed and rigidly interconnected supporting bars constitute a unitary auxiliary frame indicated at 10, which frame is yieldably carried by the receptacle-supporting framework, the yieldability achieved in a manner particularly shown in Figs. 2 and 3 and comprising springs, the purpose being to mount the moving and/or vibratory mechanisms of the machine upon the auxiliary frame so as to damp and/or reduce to a minimum the vibrations thereof reaching the floor or the outer casing.

To this end, each leg 9 securely carries a bracket or angle iron near its bottom end, the horizontal portions 11 of said brackets being substantially in a common plane and perforated so as to receive fairly snugly therein a cup 12 the outwardly turned or formed upper edge portion of which cup rests upon the upper surface of the horizontal bracket portion, as clearly shown in Fig. 3. The bottom of each cup is centrally apertured to receive therethrough a bolt 13 depending from but supported by the horizontal flange of a bar 10 constituting a portion of the auxiliary frame. A coil spring 14 is disposed around each bolt but confined for the most part within said cup, the upper end of the spring bearing against the under surface of the said bar flange, and the lower end of said spring bearing against the bottom of said cup.

Each bolt 13 is of a length to extend below its associated cup 12, the lower end of the bolt passing centrally through a saucer-like disk 15 and threaded to receive an adjusting or spring-tensioning nut 16 and lock nut 17. A coil spring 18 encompasses each cup 12, the upper end of the spring bearing against the horizontal under surface of the bracket 11, and the lower end of said spring bearing against the upper surface of the disk 15, the edge or rim portion of said disk being upwardly directed to form a positive confining seat for said lower end of the spring.

Thus it will be understood that the spring 14 counteracts, damps and/or absorbs the downwardly directed forces imparted to the auxiliary frame bar 10, and that the spring 18 counteracts, damps and/or absorbs the upwardly directed forces imparted to said bar 10. The dimensions, strengths, and other characteristics of said springs will be made in accordance with the forces exerted by and/or through the moving mechanisms supported by the auxiliary frame.

Associated with each of the tubs and supported thereby and/or by said framework, are duplicate float-valve boxes indicated at 115 and 116 each in open communication with its respective tub

as by a pipe such as indicated at 118. Each box is connected to a source of water supply as suggested by the pipe 119 associated with box 115.

An ornamental housing generally identified by the numeral 25 is provided to encase the entire machine, and 29 indicates a latch operating device for controlling the release of the spring tensioned cover 30 on top of said casing, said cover disposed over the opening 31 through which clothes are admitted to and abstracted from the machine. The cover carries an arm 36 the lower end of which is adapted to operate an electric switch not illustrated in detail but generally identified by the rectangle 37, and the numeral 39 indicates an electric conductor for supplying current for operating the machine.

On one side of the machine, the yieldable frame 10 is provided with a pair of inclined A-legs such as 45 joined by a gusset plate, and on the other side of the machine the said frame is provided with a duplicate pair of inclined A-legs as indicated at 47 also joined and strengthened by a similar gusset plate. The two pairs of A-legs are so disposed on the machine that their upper extremities may provide bearings for a rock shaft 49 extending across the machine in substantially the vertical plane of the partition separating the two tubs, said rock shaft passing through the side walls of the receptacle 2. An outer end of this rock shaft rigidly carries a segmental gear 50 carrying the cams 51, 52, 53 and 54. The central portion of the rock shaft has a U-shaped off-set as indicated at 55 to accommodate the sleeve 57 carrying a bevel gear 58 in enmeshment with a bevel pinion 59 carried by a shaft having a bearing in the hollowed section 61 of said rock shaft and extending outwardly thereof to receive the pulley 62 driven by the belt 63 from the pulley 64 mounted on the shaft 117 actuated by the electric motor 65 mounted upon the yieldable frame 10.

The sleeve 57 is rigidly secured to the center of the bottom of a cylinder 66 whose circular wall is provided with perforations indicated at 67, the top of said cylinder having a central charging opening through which clothes may be placed in and abstracted from said cylinder. Therefore it is to be understood that, so long as the electric motor 65 is energized, the cylinder 66 will be rotated about the axis of said sleeve 57 by virtue of the bevel gears 59 and 58.

In the drawings the cylinder is shown in its uppermost or raised position, but it may be lowered into the two tubs previously mentioned through the instrumentality of said rock shaft, first into one tub for soaking the clothes, then into the other tub for the washing operation, then back into the first tub for the rinsing operation. In each instance the cylinder is given a certain rate of rotation with respect to the particular tub occupied, is permitted a certain time duration for its immersion in a tub, and is permitted a pause in its orbital rocking path of travel, which pause takes place when the cylinder is in its uppermost or raised position (as illustrated) and during which pause the rate of its rotation is greatly increased so as to effect an extraction of most of the water contained in the clothes, the water thus extracted by centrifugal force being thrown laterally and collected by the trough 250 which is connected to a suitable drain.

The means for rocking the cylinder comprises the reversible electric motor 71, carried by the yieldable frame 10, the driving belt 72, and suitable geared connections including a pinion or worm enmeshed with the segmental gear 50 whose various cams control the circuit to said motor.

A rocker cam 130 is actuated by the cam 54 of the segmental gear, and through the link 132 operates a crank 136 secured to a rock shaft adapted to operate flap valves covering the discharge ends of the drain pipes 6 and 7 from the tubs, whereby the tubs are drained automatically of their liquid contents when the cylinder 66 has been rocked to bring the cam 54 into operating engagement with the rocker cam 130. A spring 154 serves normally to pull the link 132 downwardly and thereby control a lever connection with crank 136 so that the said flap valves will normally be closed.

From the foregoing it will be understood that the stationary elements of the machine are mounted so as to be supported directly on the floor, whereas the moving mechanisms are mounted upon a unitary frame 10 which is yieldably supported by the stationary framework of the machine. Hence, all of the vibrations created by the moving mechanisms are damped and/or absorbed by the yieldable connection between said frame and said framework.

Whereas, principally, in the foregoing specification the yieldable connection has been specifically set forth as comprising mechanical springs of the coil type, it is to be understood that the invention is not to be limited solely thereto. Other types of mechanical springs could readily be employed, and yieldable substances and/or material other than such mechanical springs could likewise be substituted, as for example blocks, cushions or buffers made of rubber or rubber like substances, dash-pots of either pneumatic or hydraulic principle, and adaptations of well known shock-absorber constructions. Therefore, in the claim the term spring is to be taken as inclusive of and synonymous with any suitable means which will provide the yieldable connection between the stationary framework of the machine and the unitary frame carrying the movable mechanisms.

It is obvious that those skilled in the art may vary the details of construction and arrangements of parts without departing from the spirit of this invention, wherefore it is desired not to be limited to the exact foregoing disclosure except as may be required by the claim.

What is claimed is:

In an apparatus comprising relatively static elements and movable elements, the combination of a rigid framework for supporting the static elements directly from the floor, said framework comprising a cup; an auxiliary frame upon which the movable elements are supported, said frame having a portion disposed over said cup; and yieldable connections supporting said auxiliary frame from said framework, said connections comprising a pair of tensioned springs, one spring nested within said cup and exerting its force in one direction, and the other spring encircling said cup and exerting its force in the opposite direction.

ALBERT R. MILLER.
